RELAY

Carl H. Larson, Elkhart, Ind., assignor to The
Adlake Company, a corporation of Illinois

Application October 5, 1932, Serial No. 636,286

3 Claims. (Cl. 171—97)

Standby relays are used in electrical circuits to transfer a load from our source of current to another whenever the former falls below a predetermined standard. In railway signaling systems, they are placed at intervals along the line to place the signals in local circuit should the power in the main line fall below the voltage required for clear signals.

In transferring the load from one source of current to another, it is essential that the main circuit be broken before the local circuit is established, and vice versa when the main circuit through the signal is reestablished. One object of the present invention, therefore, is to provide a time delay element that will insure a breakage of one circuit before the completion of the other.

Other objects of the invention are to provide mercury switches to take the place of the mechanical contacts heretofore employed in railway signaling systems; to provide a novel arrangement for mounting two or more mercury switches on a single operating coil; and to provide a relay which will be simple in construction, but reliable in operation.

Further and other objects and advantages of the invention will become apparent as the disclosure proceeds and the description is read in conjunction with the accompanying drawings, in which

Fig. 1 is a diagrammatic illustration of a preferred embodiment of the invention in which mercury switches of the plunger type are employed for making and breaking the circuits. The switches in this figure are shown with their plungers in the position they assume when the main coil is energized.

Fig. 2 is a diagrammatic illustration corresponding to Fig. 1 but showing the plungers in the position they assume when the main coil is deenergized;

Figs. 3, 4 and 5, are circuit diagrams showing various modifications of the invention;

Fig. 6 is a plan view showing the preferred arrangement of a multi-switch relay;

Fig. 7 is a vertical, sectional view of the relay shown in Fig. 6, taken on the line 7—7 of that figure.

Fig. 8 is a perspective view of the laminated core pieces; and

Figs. 9, 10 and 11 are perspective views of the plungers used in the several switches.

But the specific illustration of preferred embodiments of the invention and the corresponding specific description that follows are for the

purpose of disclosure only and are not to be construed as limiting the scope of the appended claims except as required by the prior art.

Referring first to Figs. 1 and 2, a preferred embodiment of the relay has been diagrammatically shown applied to a railway signal circuit. A railway signal is indicated at 20 which is normally operated on alternating current derived from the secondary coil 21 of the transformer 22, the primary coil 23 of which is connected to the power line 24. A local battery 25 is provided for operating the signal upon failure of the alternating current, and in cases when the alternating current falls below a predetermined voltage.

Four mercury switches A, B, C, and D are mounted in cooperative relation with an electromagnet 26, the coil 27 of which is energized by the primary coil 23 of the transformer at periods determined by the position of the control switch E. The winding 28 of the control switch is shunted across the primary coil 23 of the transformer by conductors 29 and 30, and consequently the strength of the magnetic field which it produces is dependent upon the voltage in the power line 24.

The switches A, B, C, D and E are mercury switches of the plunger type comprising glass envelopes 31 through the bottom of which suitable electrodes are sealed. Plungers float on the mercury 32 within the envelopes, and determine by the amount of mercury they displace which electrodes are bridged by mercury. The switches are evacuated and then filled with an inert gas as common in such constructions.

Springs 33 and 34 serve to protect the envelope from damage due to rough handling of the switch.

The control switch E has electrodes 35 and 36 sealed through the bottom of the envelope, the former being protected by a glass insulating sleeve 37 to a point 38, leaving the portion 39 of the electrode bare. The electrode 35 is connected by conductors 40 to one side of the coil 27, the other side of the coil being connected by a conductor 41 to the electrode 36 through the winding 28 of the control switch E. Sleeves 42 and 43 of suitable magnetic material, such as Swedish iron, are mounted within the spool or core sleeve 44 of the control switch E and provide an air gap 45 adapted to be closed by the plunger 46, also of magnetic material, when the coil is energized (as shown in Fig. 1). In this position of the plunger, sufficient mercury is displaced to cause the bared portion 39 of the electrode 35 to be covered with mercury, thus establishing electrical

connection between the electrodes 35 and 36 and energizing the main coil 27.

In case the voltage in the main line 24 falls below a predetermined standard, for example, below 5 low 75 volts on a normal 110 volt alternating current line, the strength of the magnetic field in the coil E is insufficient to hold the plunger 46 in depressed position against the buoyancy of the mercury and it will rise to the position shown in Fig. 2, breaking the circuit through the main coil 27 and affecting the switches A, B, C, and D, accordingly.

The switches A, B, C and D are operated by the main coil 27 by providing a pole piece 47 at the top of the switches and a pole piece 48 at the bottom of the switches. The upper and lower pole sleeves 49 associated with each switch provide suitable air gaps 50, 51, 52 and 53 for the switches A, B, C, and D, respectively. The pole pieces and the pole sleeves are made of suitable magnetic material.

Switches B and C are in the direct current circuit, the latter switch being slow acting to insure that the alternating current circuit will be broken before the direct current circuit is made when the signal 20 is being transferred from alternating current to direct current. Electrodes 54 and 55 of the switch B and electrodes 56 and 57 of switch C are connected in series with the load 20 and the battery 25, as clearly appears from the drawings.

The electrodes 54 and 56 are insulated to a point adjacent the top of the electrode by a glass sleeve, as in the control switch E. The plunger 58 of switch B assumes the position shown in Fig. 1 when the coil 27 is energized, thus breaking the circuit through the battery. The plunger 59 of switch C differs from plunger 58 of switch B in that it is closed at the top except for a small opening 60. The closure is tapered, as indicated at 61 to prevent mercury from becoming lodged on top of the plunger.

When the plunger 59 is in the position shown in Fig. 1, the air gap 52 is closed and the plunger is, preferably, completely lifted from the mercury within the envelope. This causes the mercury level to fall below and the direct current circuit is broken at a second point.

The electrodes 62 and 63 of switch A and electrodes 64 and 65 of switch D are connected in series with the load 20 and the secondary coil of the transformer 22. The plunger 66 of switch A assumes the position shown in Fig. 1 when the coil 27 is energized, thus covering the electrode 62 with mercury and closing the alternating current circuit on the one side of the load.

The plunger 67 of switch D normally is in the position shown in Fig. 1 and in this position, the electrode 64 is covered with mercury, completing the alternating current circuit through the load.

It will thus be seen that under normal conditions, the control switch E energizes the main coil 27 and completes the alternating current circuit through the signal 20 by bridging electrodes 62 and 63, and 64 and 65 of switches A and D, respectively, while holding the direct current circuit open by breaking the connections between electrodes 54 and 55, and 56 and 57 of switches B and C, respectively. If the power in the line 24 falls below a predetermined voltage, say 75 volts, the plunger 46 of control switch E, due to its buoyancy and the insufficient strength of the magnetic field, rises and uncovers the electrode 35. Immediately thereupon the coil 27 is deenergized and the plungers 66 and 67 of switches A

and D rise, due to their buoyancy, and the plungers 58 and 59 of switches B and C fall, due to gravity.

Switches A and B being quick acting, will break and make their connections substantially instantaneously. The switch D will break the alternating current circuit at a second point shortly thereafter. Switch C, however, delays the completion of the direct current circuit by forming a gas trap within the plunger 59 and allowing the gas within the plunger to slowly escape through the vent 60.

In this way, the mercury is kept away from the electrode 56 even when the plunger is in the position shown in Fig. 2 until the pressure on the inside and outside of the plunger is equalized by the escape of gas through the vent 60.

Conversely when the load is transferred from direct current to alternating current, which happens whenever the alternating current in line 24 picks up to some predetermined voltage, the plunger 46 in control switch E is again depressed into the mercury and the main coil 27 is energized, whereupon the direct current circuit is broken immediately at switch B and at substantially the same time at C (the plunger in this case being lifted completely out of the mercury and causing a quicker break than in switch D), and the alternating current is made by the action of switches A and D, the latter switch providing a sufficient interval of time before closing the alternating current circuit to insure that the direct current circuit is previously broken.

Referring now to Figs. 3, 4 and 5, there has been illustrated three adaptations of the present invention to mechanical relays. Although in each instance, the four electromagnetic switches which control the making and breaking of the direct and alternating current circuits are shown as energized by separate coils, it will be understood that they may be energized by a single coil if desired.

As before, the reference character 24 designates a source of alternating current connected to the primary coil 23 of a transformer 22, the secondary coil 21 of which is adapted to be connected through switches A and D to the signal 20.

In case of failure of the primary source of energy, the signal is adapted to be operated on a local battery 25 by the action of switches B and C, the switches A and D duly breaking the alternating current circuit. The action of all four switches A, B, C and D, is controlled by switch E which in Fig. 3 is shunted across the primary coil 23 of the transformer and in Figs. 4 and 5 is shunted across the secondary coil of the transformer. Switches C and D are slow acting so that switch C, before completing the direct current circuit provides an interval of time to insure the operation of switch A, and switch D before completing the alternating current circuit, provides an interval of time to insure the operation of switch B.

Figs. 3 and 5 differ from each other only in that the control switch E in the latter is connected across the secondary coil in the transformer, while in the former, it is connected across the primary coil.

Fig. 4 differs from Fig. 5 only in that the switch E is placed in the alternating current circuit of the signal, thus furnishing three switches in that circuit to insure proper breaking of the circuit before the direct current circuit through the signal is made.

The function of switch E in Fig. 4 can be clearly understood by observing that when the switch is energized, as shown in the figure, the coils of

switches A, B, C and D are connected in series with the secondary coil of the transformer and at the same time the alternating current circuit through the signal 20 includes the armatures of switches D, E and A.

The springs 68 associated with the armatures E, A and D, in Figs. 3-5 inclusive indicate that the armatures are held away from their associated contacts when the coils are deenergized and, therefore, correspond to the buoyancy of the mercury in the mercury switch adaptation of this invention.

A further description of the embodiments of the invention shown in Figs. 3-5 is believed unnecessary in view of the specific description of the relay shown in Figs. 1 and 2. It will be understood that the circuits of Figs. 3, 4 and 5 are equally applicable to the mercury switch relay of Figs. 1 and 2.

Figs. 6-11 inclusive illustrate certain of the physical characteristics of the mercury switch embodiment of this invention. As there shown, the coil 27 is wound upon a spool 69 substantially square in cross section. L-shaped laminated core pieces 70 are adapted to be placed in the spool in the manner shown in Fig. 6, the long arms 71 of each core piece being offset at 72 to receive the correspondingly formed core piece which is inserted from the other end of the spool. The short arms 73 of the core pieces project radially toward the margin of the coil, as indicated in Fig. 6. Suitable metal clips 74 are used to clamp the pole sleeves 49 to the arm 73 and through these sleeves the mercury switches themselves are mounted. Rubber gaskets 75 are applied to the tops and bottoms of the switches, as shown in Fig. 7 to hold the switches firmly in place.

The coil 27, being operated on alternating current, has increased efficiency when the core pieces are laminated as shown.

It will be noted that the plungers in Figs. 9, 10 and 11 are provided with either lugs or notched flared ends which space the plungers from the envelopes without interfering with the passing of mercury on the outside of the plunger.

It will be understood that the various coils, switch characteristics, etc. may be made to suit the particular conditions of service for which the relay is to be used, but by way of illustration, the coil 27, if operated on 10 volt A. C. may have 200 turns of 19 gauge enameled wire having a

current consumption of 1.7 watts. The coil of the control switch E under such conditions may have 1000 turns of No. 26 gauge enameled wire with a current consumption of .3 of a watt. If the relay is operated at 110 volt A. C., as shown in Figs. 1-2, the coil for operating the four switches may have 2300 turns of No. 29 gauge enameled wire drawing 1.75 watts. In such case, the control coil of the switch E would have 15,000 turns of No. 26 gauge enameled wire, consuming .3 of a watt.

What I claim is:

1. In combination, a primary circuit including a source of electrical energy and a load, an auxiliary circuit including another source of electrical energy and the same load, means responsive to pressure in the primary circuit for determining which of said circuits will operate the load, said means including a pair of independently operating circuit breakers in the main circuit, one on each side of the load, and one being slow acting, and a like pair of circuit breakers in the auxiliary circuit, also on opposite sides of the load, and one being slow acting, said slow acting circuit breakers in the primary and auxiliary circuits serving to insure that the transfer of the load from one circuit to the other will be effected without overlap.

2. In combination, a primary circuit, an auxiliary circuit, a load adapted to be operated from either of said circuits, a fast acting relay and a slow acting relay in each circuit, means responsive to pressure in the primary circuit for operating said relays, said slow acting relays preventing an overlap in the circuits when a transfer is being made from one to the other.

3. In combination, a primary circuit, an auxiliary circuit, a load adapted to be operated from either of said circuits, a fast acting relay and a slow acting relay in each circuit, said relays comprising vertically mounted switch envelopes having contacts hermetically sealed within the envelopes, mercury in the envelopes adapted to be manipulated to make or break the circuit through the contacts and magnetically controlled displacers for shifting the mercury, means responsive to pressure in the primary circuit for operating said relays, said slow acting relays preventing an overlap in the circuits when a transfer is being made from one to the other.

CARL H. LARSON.
